LID REMOVER FOR WALL CAN OPENERS

Roy E. Wester, Greeneville, Tenn.

Application June 17, 1949, Serial No. 99,733

1 Claim. (Cl. 248—204)

1

This invention relates to a can lid remover attachment for a wall supported can opener.

The conventional wall supported can opener in general use has one disadvantage that is a decided inconvenience to the user. This disadvantage resides in the fact that upon full severance of the top or lid from the body of the can, said lid becomes quite difficult to remove. Generally, it drops upon the contents of the can, and when one attempts to remove the lid by tilting, one's fingers become immersed in said contents of the can, and additionally, the lid often tilts into said contents, forcing them over the side of the can. If one attempts to remove the lid by inserting a fork or similar implement thereunder, it is often difficult to enter the fork in the space between the severed lid and the can wall.

It is to remedy these inconveniences that the present invention is designed.

Another important object of the present invention is to provide an attachment of the character described that can be readily secured to the body of a can opener of the type referred to, and which will not require modification of the can opener construction in any way.

Still another object is to provide a device of the type stated which is applied with complete speed and ease to the can the lid of which is to be removed.

With the foregoing and other objects in view which will appear as the description proceeds, the invention consists of certain novel details of construction and combination of parts, herein-after more fully described and pointed out in the claim, it being understood that changes may be made in the construction and arrangement of parts without departing from the spirit of the invention as claimed.

Referring to the drawings,

Fig. 1 is a perspective view of a can attachment constructed in accordance with the invention, as it appears when applied to a conventional wall supported can opener, a can to which the attachment is applied being shown in dotted lines.

Fig. 2 is an enlarged section through the head of said attachment.

Referring to the drawings in detail, 5 designates a conventional can having the lid 6 the marginal portion of which is adapted to be severed by a cutter 7 carried by the body 8 of a conventional wall supported can opener having the rotatable handle 9 for rotating the toothed gear 10, said toothed gear 10 being disposed under the head of the can for rotating the can to sever the lid therefrom.

All the above parts are wholly conventional, and do not per se constitute part of the present invention.

The present invention includes a bracket 11 secured to the body 8 of the can opener by screws 12 and having the vertically disposed recess 13 through which extends, for rotatable movement within the recess, the spindle 14 having the laterally extended end 15 to prevent the spindle from dropping out of the recess. Said spindle 14 and laterally extended stop 15 can be integrally formed from a suitable length of spring wire material, said spindle merging into the coil spring 16 which in turn merges into the outwardly extended elongated arm 17 having at its free end the eye 18 through which is loosely extended the threaded stud 19 embedded in the rubber suction cup 20, knob 21 being threaded upon said stud for the purpose of holding the suction cup assembled with the arm 17. Thus, the rubber suction cup is mounted for rotatable movement upon the end of said arm, so that the cup can rotate with the lid 6 of the can 5, when the can is being rotated during severing of the lid.

25 In use, the rubber suction cup 20 normally lies close to the body 8. When a can is to be applied to the can opener, the arm 17 is swung outwardly, this being permitted by the rotatable mounting of the spindle 14 in the bracket 11, and the rubber suction cup 20 is positioned centrally of the lid 6 and is pressed thereagainst so as to set up a gripping action. Now, the handle 9 of the can opener is rotated, rotating the can 5 and cutting the lid 6 around its margin. During the rotation of the can 5, the rubber suction cup 20 is permitted free rotation with the lid.

30 35 In this connection, it will be understood that the spring 16 normally holds the arm 17 slightly elevated relative to the lid of a can applied to the can opener, so that when the rubber suction cup 20 was applied to said lid, it was applied against the action of the spring. As a result, as soon as the can opener is operated so as to fully sever the lid 6 from the can 5, the spring action, no longer restrained, elevates the rubber suction cup 20 and the lid 6 so that said lid 6 clears the can 5.

40 45 In this connection, it will be understood that it is not essential that the lid 6 clear the can 5 when fully severed therefrom. This is by reason of the fact that separation of the can body from the can opener after severing of the lid permits the body of the can to be taken from the can opener, while the lid 6 will still be held by the rubber suction cup. However, I have found it advantageous to provide a construction as described,

so that when the can body 5 is removed from the can opener, all possibility of its catching upon the marginal portion of the lid 6 will have been eliminated.

Important characteristics of the invention reside in its ready attachment to a conventionally constructed can opener, its low cost of manufacture, small number of moving parts, ready application to cans of different diameters, and ease of application to and removal from a can lid, the device being applied to the can lid simply by pressing downwardly upon the knob 21.

What is claimed is:

A device of the class described comprising a coil spring formed from a single length of wire material, one end portion of said length of wire material being extended laterally from one end of the spring to define a spindle; a bearing bracket having a pivot recess, said spindle being pivoted in said recess, the pivot axis of the spindle 15

being substantially vertically disposed and the coil spring extending horizontally and radially away from said pivot axis; a long arm of wire material integral with the other end of the spring and proportioned to be flexed springably both horizontally and vertically; and a suction cup rotatably mounted upon and depending from said arm.
